UNITED STATES PATENT OFFICE.

JOHN K. STEWART, OF CHICAGO, ILLINOIS.

ALARM DEVICE.

No. 851,261.

Specification of Letters Patent.

Patented April 23, 1907.

Application filed March 28, 1906. Serial No. 308,390.

To all whom it may concern:

Be it known that I, JOHN K. STEWART, a citizen of the United States, residing at Chicago, in the county of Cook and State of Illinois, have invented new and useful Improvements in Alarm Devices, of which the following is a specification, reference being had to the accompanying drawings, forming a part thereof.

10 The purpose of this invention is to provide a device especially adapted for use upon automobiles and other rapidly traveling road vehicles for sounding an alarm which may be distinguished at a greater distance than the ordinary gongs or pneumatic horns.

It is in general of the nature of a siren having particular construction and adaptation to the specific use mentioned and consisting of the construction set out in the claims.

20 In the drawings:—Figure 1 is a partly sectional side elevation of a device embodying the invention, certain parts being broken away to show interior construction, which section as to such parts being at the line 1—1 on Fig. 2. Fig. 2 is a section at the line 2—2 on Fig. 1. Figs. 3 and 4 are detail sections looking in opposite directions at the line 3—4 on Fig. 2.

The device shown in the drawings comprises a fixed cylindrical case, 1, having a multiplicity of peripheral mouths or apertures, 2^a, 2^a, 2^a, in the peripheral enclosing wall, 2, of the casing, having mounted in it for rotation a vaned wheel comprising a hub, 4, a closed circular side plate, 4^a, vanes, 4^b, and a centrally apertured opposite side plate, 4^c. This wheel is adapted to operate after the manner of a centrifugal blower or fan taking in the air at the central aperture, 4^d, of the side plate, 4^c, and imparting to the air from the rotation of the wheel centrifugal movement causing it to be discharged peripherally from between the vanes through the apertures, 2^a, of the case. The portions 35 of the peripheral wall, 2, of the case intervening between the apertures, 2^a, are preferably somewhat longer than the apertures, and the vaned wheel has also an interrupted peripheral wall consisting of segmental portions, 4^e, 40 extending in one direction circumferentially from each vane toward the succeeding vane, closing a portion of the mouth through which the air is discharged from between the vanes and reducing said mouth to the openings, 4^f, 45 which are preferably approximately equal to the openings, 2^a, of the case. It may be un-

derstood that when this wheel is rotated at high speed the air taken in through the central opening and impelled centrifugally will be discharged in interrupted puffs through each 60 of the apertures, 2^a, and such puffs following each other at high speed will produce a musical note or tone varying with the speed of rotation, according to the familiar principle of the siren. For rotating this wheel at sufficient speed to cause a musical note to be sounded and to render it possible to make such note of as high pitch as desirable for the purpose of an alarm, I provide a speed train which will now be described.

The case, 1, which may be open at the outer side has its inner side formed by the diaphragm, 2^b, upon which there is mounted at a central opening and protruding therethrough into the case, a bearing post, 6. 70 This bearing post has a flange, 6^a, for securing it to the case, the flange projecting from a hollow or tubular portion, 6^b, of the post. Said tubular portion protrudes into the case and into the hollow hub, 4, of the 80 wheel therein. The outer end portion of the post, 6, is reduced in diameter to afford bearings for certain parts of the train hereinafter described. Located axially within the hub, 4, of the wheel and secured thereto 85 is a spindle, 7, which is reduced in diameter at its outer end to fit snugly within the correspondingly reduced outer end of the hub to which it is made fast at that point by the pin, 7^a. The inner end of the spindle is reduced for mounting loosely on it the pinion, 7^d, which is adapted to drive the shaft one way, as hereinafter described. The pinion and spindle carry respectively the seats for ball bearings, 9, 9^a, which are interposed 90 between them and the post, 6, the collar, 10, being screwed into the end of a hollow portion, 6^b, of the hub for retaining the balls, 9^a. On the diaphragm, 2^b, of the case, 1, there is mounted the gear train case, 11, which at the side remote from the case, 1, affords a support at 11^a, to the outer end of the post, 6, on to which there is screwed at this point a collar, 6^d, which forms the adjustable member of the ball case for a ball bearing, 12, which is provided for one member of the train as hereinafter more particularly described. A shaft, 13, supported at one end in the diaphragm, 2^b, of the case, 2, and extending out through, and obtaining another support in, the outer wall of the gear case, 11, has mounted upon it outside

the gear case a pedal lever arm, 14. On this shaft within the gear case there is mounted a gear wheel, 15, which has on one face a ratchet flange or rim, 15^a, and the 5 pedal, 14, carries a dog, 14^a, which protruding through a segmental slot, 11^b, in the case, 11, engages the ratchet rim, 15^a, a spring, 14^d, being provided to retract the pedal to 10 carry the dog back over the ratchet. The 10 dog is preferably a serrated segment, 14^a, having a stem, 14^b, a shoulder, 14^c, about the stem back of the segment head for stopping a spring, 15^d, which is coiled around the stem and stopped opposite the shoulder on 15 the socket piece, 15^e, which is set into the lever arm, 14, for that purpose, the dog being retained by housing, 15^e, engaged with the socket piece and having a segmental slot for the segmental serrated head, 14^a. 20 The purpose of the serrated head instead of a single tooth is to afford more powerful engagement with the ratchet rim, 15^a, notwithstanding the preferably fine teeth of the latter. A collar, 16, on the shaft, 13, forms 25 a stop for the wheel, 15, on the side opposite the ratchet disk, and also one member of a ball case for the ball bearing, 16^a, of a combined gear-and-pinion, 17-18, having a long hub by which it is mounted on the shaft, 13, 30 one end of the hub co-operating with the collar, 16, to form the ball case for the bearing, 16^a, and the other end of the hub similarly co-operating with the bearing plate, 19, mounted on the diaphragm, 2^a, of the 35 blower case. On the inner reduced end of the spindle, 7, there is mounted loosely for rotation the pinion, 7^d, already mentioned, having the end toward the shoulder, caused by reducing the spindle, provided with two 40 ratchet teeth, 7^e; and in the shoulder of the spindle there is lodged a spring-pressed pin, 7^f, which is thrust out by its spring, 7^g, for engagement with the shoulders, 7^e, to enable the pinion to rotate the spindle in one 45 direction while permitting said spindle and the siren wheel to run faster than the pinion in the same direction. The hollow or tubular portion, 6^b, of the post, 6, is apertured at one side in the zone of said pinion, 50 7^d, and through this aperture the gear, 18, protrudes for engagement with the pinion. On the reduced portion of the post, 6, there is mounted a combined gear and pinion, 20-21, whose long hub is journaled on the 55 reduced portion of the post, one end of the hub co-operating with the sleeve, 6^b, to form a ball case for the ball bearing, 12, at that end, the other end being similarly adapted to co-operate with the shoulder 60 of the post which is formed by reducing it, to form the case for the ball bearing, 22. The pinion, 21, of this combined gear and pinion meshes with and is driven by the gear, 15, and the gear, 20, meshes with and 65 drives the pinion, 17, of the combined wheel,

17-18. With this construction, it will be understood that the operator by means of the pedal, 14, can give a very high rotary speed to the vaned wheel within the blower case.

The fixed parts,—namely, the case, 2, and the case, 11,—or either of them, may be provided with any suitable flanges, 23, 23^a, for mounting the devices fixedly in any convenient position in the vehicle with which it is to be used, so as to locate the foot piece, 14^e, of the pedal, 14, in convenient position for operation as described. With a device of this character having the rotary wheel not more than six inches in diameter, a speed of 80 rotation is easily obtained which will sound a musical note of proper pitch and loudness to be heard for a distance of several miles in an open country; and the gradual rise and fall of the speed causing a gradual rise and fall of the pitch makes the warning note which is sounded peculiarly recognizable. For modifying the loudness while permitting the full range of pitch, a regulating shutter, 25, may be provided encompassing the apertured periphery of the case, 2, having its end apertures corresponding to those of the case and adapted to be adjusted through a short angle about the case to close more or less the apertures, 2^a, of the latter. A flange, 25^a, extending on to the diaphragm, 2^b, of the case, 90 may be provided with two or more segmental slots, 25^b, through which screws, 26, may extend into the diaphragm plate for securing the shutter at any position to which it may be adjusted within the range of the slots.

I claim:—

1. An alarm device comprising a siren wheel and a case; a speed train mounted on the exterior of the siren-wheel case and a supplemental case also mounted on the siren-wheel case enclosing said speed train, the two cases together affording bearings for the train; a wheel of the train having a ratchet rim; an operating lever mounted on the train case exteriorly thereof and a dog carried thereby engaging the ratchet rim, the case being apertured to admit the dog to the rim.

2. An alarm device comprising a fixed case and a rotatable vaned wheel therein, the case having a multiplicity of apertures corresponding to the chambers between the vanes and the case and wheel being adapted to admit the air to said inter-vane chambers about the center; means for mounting and rotating the wheel comprising a post rigid with the case having a tubular hollow portion protruding thereinto, the wheel having a hollow hub which receives said protruding portion of the post, and a spindle located axially within said hollow hub which protrudes into the hollow portion of the post; a gear pinion rigid with said spindle, the hollow post being apertured in the zone of said gear pinion, and a speed-multiplying train of gears mount-

ed on the case having a gear which protrudes through said aperture for engagement with said pinion within the hollow post.

3. An alarm device comprising a fixed case 5 having a multiplicity of apertures and a siren wheel therein, the wheel and casing being apertured at one side about the center for air induction; a gear case mounted on the opposite side of the siren wheel case; a speed- 10 multiplying gear train in said gear case for rotating the siren wheel; an operating lever outside the gear case mounted for rocking about the axis of the first wheel of the train, the side of the gear case having a segmental 15 slot, the first wheel of the train having a ratchet flange and the operating lever having a pawl which protrudes from the slot for engaging the ratchet.

4. An alarm device comprising a case having 20 a multiplicity of peripheral apertures; a rotary vaned wheel within the case having corresponding apertures leading from between its vanes, the case and wall being constructed to close such spaces between the 25 vanes except at the center and at said apertures; a speed gear train mounted on the case for rotating the wheel; a case inclosing the gear train and mounted rigidly on the alarm case; a shutter mounted loosely on the alarm 30 case encompassing the latter, having aper-

tures corresponding with the peripheral apertures of the latter and rotatable thereabout at will to cover said apertures more or less.

5. An alarm device comprising a siren wheel and its case; a gear train mounted on 35 the case for rotating the siren wheel, and a clutching device interposed in the train for communicating driving movement to the siren wheel in one direction only, adapted to permit the wheel to run faster than the train 40 in said direction.

6. An alarm device comprising a siren wheel and a case for the same; a speed-multiplying train mounted on the case operatively connected with the siren wheel for rotating 45 it; an oscillating lever and a pawl-and-ratchet connection between the same, and a wheel on the train for driving the train in one direction, and a clutch device interposed between the train and the siren wheel for driving the 50 latter in one direction and permitting it to run faster than the train in that direction.

In testimony whereof, I have hereunto set my hand at Chicago, Illinois, this 26th day of March, A. D., 1906.

JOHN K. STEWART.
